(57) CLAIM

The ornamental design for a furniture pillow, as shown and described.

DESCRIPTION

FIG. 1 is a top, front, right perspective view of the claimed design for a furniture pillow;

FIG. 2 is a bottom, rear, right perspective view thereof;

FIG. 3 is an enlarged top, front, right perspective view thereof;

FIG. 4 is an enlarged, top, rear, left perspective view thereof;

FIG. 5 is an enlarged front view thereof;

FIG. 6 is an enlarged rear view thereof;

FIG. 7 is an enlarged left view thereof;

FIG. 8 is an enlarged right view thereof;

FIG. 9 is an enlarged top view thereof; and,

FIG. 10 is an enlarged bottom view thereof.

The broken lines immediately adjacent to the shaded area on the hook depict boundaries of the claimed design and form no part thereof. Additional broken lines on the furniture pillow show portions which are not part of the claimed design. The furniture shown in broken lines in FIGS. 1 and 2 depict environment and is not part of the claimed design.
